ORDNANCE

John C. Trotter, Williamsville, and Carl F. Carlzen, Buffalo, N. Y., assignors to Bell Aircraft Corporation, Buffalo, N. Y.

Application February 9, 1942, Serial No. 429,985

5 Claims. (CL 89—33)

This invention relates to ordnance, and more particularly to means for feeding belts of ammunition to rapid fire guns, such as machine guns or the like.

One of the objects of the invention is to provide an improved mechanism for the above described purpose which comprises a self-contained cartridge belt feed assist mechanism adapted to be mounted adjacent a gun and as an accessory thereto for propelling the ammunition belt in accord with the gun feed requirements from the region of a remotely disposed ammunition magazine, whereby the usual ammunition feeding mechanism of the gun per se will be relieved of forces necessary to elevate the ammunition belt and to accelerate its movement into the gun mechanism. Another object of the invention is to provide a mechanism of the character described which is of improved adjustability so as to be adapted to suit a variety of cartridge belt training arrangements. Another object of the invention is to provide a device of the character described which is of improved structural form so as to be positive in action and of structurally simple and rugged form. Another object of the invention is to provide a device of the character described which is adapted to start and stop in connection with intermittent gun feeding operations in an improved manner. Other objects and advantages of the invention will appear from the specification hereinafter.

In the drawings:

Fig. 1 is a top plan of a cartridge belt feed accessory mechanism of the invention;

Fig. 2 is a section taken substantially along line II—II of Fig. 1;

Fig. 3 is a section taken along line III—III of Fig. 2; and

Fig. 4 is a section taken along line IV—IV of Fig. 2.

The drawings illustrate the invention as comprising a self-contained motor-driven ammunition belt propelling mechanism which is adapted to be disposed adjacent the usual ammunition feedway portion of a machine gun or the like for elevating and propelling the usual belt of linked ammunition, as indicated at 10 (Fig. 3) toward the feedway port of the gun. The ammunition belt is illustrated as comprising a series of cartridges 12 arranged in side-by-side relation and united in articulated connection relation by means of links 14 (Fig. 2).

The feed assist mechanism is arranged to drive the cartridge belt 10 in a direction from right to left as viewed in Fig. 3; and thus it will be under-

stood that the cartridge belt will be arranged to train from the ammunition magazine (not shown) into the feed assist mechanism at the right hand side thereof as viewed in Fig. 3 for discharge at the left hand side thereof; and that the associated gun will be located generally adjacent the left hand side portion of the feed assist mechanism.

The feed assist mechanism is illustrated as comprising a cartridge belt guide or throat portion 16 which is rectangularly tubular to accommodate the cartridge belt 10 so as to be continuously freely slidable therethrough. Bracket portions 18—19 extend at opposite sides of the throat portion 16 and intermediately of its length to provide suitable bearing portions to rotatably support a pair of transverse shafts 20—22 arranged in parallel relation above and below the throat portion 16, respectively. Bushings 23 are provided to reduce shaft rotation friction effects. The shaft 20 mounts in keyed relation theron spaced large and small sprocket wheels 24—25 respectively, to engage at their toothed portions successive cartridges of the cartridge belt as it feeds through the throat 16. The toothed portions of the sprockets 24—25 are formed so as to complement the smaller and larger diameter portions of the successive cartridges, as illustrated in Fig. 2. The shaft 22 mounts a similar pair of large and small sprocket wheels 26—27 which are arranged to oppose the corresponding sprocket wheels 24—25; and thus the cartridges of the ammunition belt are adapted to be successively engaged simultaneously by the sprocket wheels 24—25—26—27 in geared relation therebetween.

The shaft 22 extends at one of its ends beyond the corresponding bearing block portion of the device to engage in keyed relation with the inner end of a clock-type spring 30. For this purpose the shaft 22 may be conveniently angularly sectioned, as indicated at 32 so as to be adapted to engage in keyed relation with a similarly sectioned inner end portion of the spring (Fig. 4). At an intermediate portion of the shaft 22, it carries in keyed relation theron a spur gear 34 which meshes with a similar spur gear 36 keyed to an extending end portion of the shaft 20. Thus, it will be understood that whenever the coil spring 30 is tensioned to provide torque forces relative to the axis of the shaft 22, the torque forces will be transmitted simultaneously to the shaft 20.

A housing portion 40 extends longitudinally of the shaft 22 to provide a tubular bracket device for supporting an electric motor housing 42 when

slidably inserted therewithin. The bracket 40 is of the split wall type adjacent its outer end portion and formed with registering eye portions 43 (Fig. 4) for engagement by a bolt-nut connection device 44, whereby the motor 42 may be readily assembled or disassembled relative to the remainder of the mechanism. The motor 42 carries an extending shaft portion 46 which is keyed to a flange 48 by means of a pin 49. The flange 48 is formed with a peripheral shell portion 50 encompassing the clock spring 30. The shell 50 is perforated as at 52 (Fig. 4) to receive an outwardly turned end portion of the clock spring 30, whereby the latter is keyed to the flange 48. Consequently, it will be understood that when the motor 42 operates to rotate the shell 50, the clock spring 30 will thereby be tensioned to transmit the torque of the motor to the sprocket shafts 20-22 for driving the cartridge engaging sprocket wheels thereof in opposite directions to propel the cartridge belt toward the position of the gun.

The motor 42 is arranged to be controlled by an automatic switch mechanism, and it will be understood that the power supply circuit of the motor will be connected to any suitable power source such as a storage battery or the like, as may be preferred. The motor control mechanism includes a micrometer switch illustrated at 54 as being mounted upon the upper portion of the throat-structure 16; and the actuating finger element of the switch 54 is indicated at 56 as being in alignment with the extending end portion of a screw 58 threaded through a side arm portion 60 of a tubular casing 62. The casing 62 is telescopically mounted upon a stem 64 which is in turn pivotally connected by means of a pin 66 to an upstanding bracket portion 68 of the feed throat structure so that the stem portion 64 extends into an open end of the casing 62 to bear against a compression spring 70 disposed within the casing. At its opposite end the casing 62 is carried by means of a pivot pin connection device 72 upon an end portion of a forked bell crank 74 which rotatably mounts upon the sprocket shaft 20 by means of a pair of bushings 76-76 to straddle a ratchet gear 78 which is keyed to the shaft 20 midway of the positions of the sprocket wheels 24-25 thereon. At its opposite end portion, the bell crank 74 mounts by means of a pivot pin 80 a U shaped ratchet pawl 82, and a coil spring 84 is mounted thereon so as to urge the pawl 82 at all times to move into meshed engagement with the ratchet 78.

A pair of crank arm portions 86-86 are formed to extend from the ratchet pawl 82 and diametrically opposite thereto to carry a lever 87 thereon by means of a pivot connection 88 and a releasable clamp bolt and slot connection 89. A cartridge belt engaging roller 90 is carried by the outer end of the lever 87; and it will be understood that the adjustable connection device 89 will be arranged in any given case in such manner that the roller 90 is disposed to bear against the cartridge belt 10 as it trains between the position of the ammunition feed assist device and the ammunition feedway portion of the gun.

Thus, it will be understood that whenever the gun commences firing the cartridge belt portion between the positions of the gun and the feed assist mechanism will be tautened to lift the lever-arm device 86-87 whereby the ratchet pawl 82 will be swung away from engagement with the ratchet 78. Simultaneously, the entire bell crank unit 74 will be rotated in clockwise direction (Fig.

3) about the shaft 20 in response to the lifting forces applied by the cartridge belt against the roller 90, whereby the casing 62 will be forced to move telescopically over the stem 64 against the action of the spring 70. Finally, the screw 58 will come into contact with the micrometer switch actuating element 56 to actuate the latter in such manner as to close the power supply circuit of the motor 42. Thus, the motor will be energized to tension the clock spring 30 and the sprocket wheels 24-25-26-27 will be driven thereby in such direction as to propel the cartridge belt 10 to move toward the machine gun, thus relieving the feed pawl mechanism of the gun per se of the loads incidental to lifting the ammunition belt to the elevation of the gun and accelerating the speed of ammunition belt movement upon commencement of each gun firing operation.

20 Upon cessation of the gun firing operation, the portion of the cartridge belt disposed between the region of the gun and the ammunition feed assist mechanism will become relaxed, whereby the roller end portion of the bell crank and lever unit will be permitted to lower and the bell crank will be permitted to rotate in counterclockwise direction as viewed in Fig. 3 in response to the action of the spring 70. Consequently, the contact finger portion 56 of the micrometer switch actuating mechanism will withdraw from operative contact with the micrometer switch element 58, and the power supply circuit to the motor 42 will thereby be opened.

25 Due to the fact that a machine gun starts and stops its firing operations with extreme suddenness, the starting and stopping of feeding movements of the cartridge belt into the machine gun ammunition feed mechanism must also occur with extreme rapidity. Hence, for example whenever a firing operation ceases, feeding movement of the ammunition belt into the gun feed pawl mechanism is stopped with extreme suddenness. The micrometer switch actuating mechanism and the sprocket wheel locking pawl 82 are thereupon operated as explained hereinabove to lock the sprocket wheels 24-25-26-27 and to open the power supply circuit of the motor 42. However, due to the inertia of the motor armature and the resiliency of the clock spring 30, the motor armature will be permitted to decelerate less rapidly than the sprocket units 24-25-26-27; while the extra movement of the motor armature is absorbed by the spring 30 and translated into further tensioning thereof. A ratchet 95 is pivotally mounted upon the housing 40 by means of a pin 96 and is elastically controlled by means of a spring 97 to engage a ratchet toothed peripheral portion 98 of the flange 48 to prevent retrograde rotation of the shell 50 upon stoppage of the motor 42.

30 Consequently, the energy stored within the spring 30 incidental to each interruption of the gun firing operation will be retained within the spring 30 pending recommencement of gun firing. 35 Upon each recommencement of gun firing the pawl 82 will be lifted as explained hereinabove by tightening of the cartridge belt between the positions of the gun and of the feed assist mechanism; the sprocket wheels 24-25-26-27 will thereupon be released, and the tension force within the spring 30 will thereby be enabled to drive the sprocket wheels in the direction of cartridge belt feeding. Thus, an initial driving of the sprocket wheels by the spring 30 will be provided instantaneously upon release of the pawl 82 to meet the

initial ammunition feeding requirements of the gun. However, as explained hereinabove, the bell crank mechanism will be simultaneously operated to actuate the motor control switch 54 in such manner as to energize the motor 42, and the latter will be accelerating simultaneously and coming up to full speed as the extra tensioning of the spring 30 is being expended.

It will be understood that the lever 87 may be adjusted by means of the connection device 89 to extend from the crank arm portions 86-86 in any angular relation thereto as may be required to dispose the cartridge belt contacting roller 90 in suitable bearing relation against the cartridge belt in view of the direction of its training between the positions of the feed assist device and of the associated gun. Thereupon, as each firing operation of the gun commences, the pulling of the cartridge belt into the feed pawl mechanism of the gun will tighten the cartridge belt so as to lift the lever arm 87 from the position of Fig. 3 to release sprocket wheels for driving by the spring coupling 30 and actuation of the motor control switch 54 to energize the motor 42, as explained hereinabove. It will be understood that the motor 42 will be selected to possess such power and speed characteristics that the sprocket wheels will be driven thereby at speeds commensurate with the cartridge belt feed requirements of the associated gun; or in the alternative, the motor-sprocket mechanism will be designed to drive the sprocket wheels at speeds slightly in excess of speeds commensurate with the gun feeding requirements. In the latter case the speed differential will be translated into intermittent storage of over-running action within the elastic coupling spring 30 and slackening of the cartridge belt between the position of the feed assist mechanism and the position of the gun ammunition feedway whereby the drive motor operation will be intermittent but always in full accord with the ammunition feed requirements of the gun.

Thus, it will be appreciated that the ammunition feed assist mechanism of the invention comprises a self-contained device of structurally simple and rugged form and which is in the nature of an accessory unit adapted to be conveniently disposed adjacent an automatic gun and to function automatically in accord with the gun ammunition feed requirements to elevate the gun feed ammunition to the region of the gun, as from a magazine or the like at a position remote from the gun, and to accelerate the movement of the ammunition toward the gun upon commencement of each gun firing operation, in improved manner.

Although only one form of the invention has been shown and described in detail, it will be apparent to those skilled in the art that the invention is not so limited but that various changes may be made therein without departing from the spirit of the invention or the scope of the appended claims.

We claim:

1. An accessory device for use in conjunction with a machine gun or the like for motivating linked ammunition rounds into the region of the gun, comprising in combination, a base, a rounds engaging member mounted upon said base and movable to propel a belt of linked rounds, motor means, tensionable elastic coupling means interconnecting said rounds engaging member and said motor means, a stop member carried by said base, means normally biasing said stop member so as to engage and stop said rounds engaging
- 75
- member and movable to release said rounds engaging member, means connected to said stop member and adapted to engage the ammunition belt between the positions of the gun and of said accessory device for moving said stop member between stop and release positions in response to alternate slackening and tightening of said ammunition belt portion, and motor control means connected to said stop member and operable in response to movement thereof to control operation of said motor means.
  2. An accessory device for use in conjunction with a machine gun or the like for motivating linked ammunition rounds into the region of the gun, comprising in combination, a throat device adapted to guide a belt of ammunition in sliding relation therethrough, a sprocket rotatably mounted upon said throat device for engaging the cartridge belt in geared relation, an elastic coupling connected to said sprocket, motor means connected to said coupling for driving said sprocket therethrough, a ratchet-pawl device mounted in connection with said sprocket and normally biased to stop ammunition belt propelling movement thereof, lever means pivotally mounted upon said device and having an end portion arranged to bear against the cartridge belt between the position of said accessory device and of the gun and being pivotable in response to tightening of said ammunition belt to disengage said ratchet-pawl device and to simultaneously control said motor means so as to become operative.
  3. An ammunition feed device comprising a self-contained mechanism adapted to be employed adjacent the ammunition feedway of a machine gun or the like for substantially relieving the ammunition feed mechanism of the gun of loads incidental to elevating and/or motivating the feed ammunition to the region of the gun from position remotely therefrom and of the loads incidental to accelerating said feed ammunition movement incidental to commencement of each gun firing operation, said feed device comprising a frame having an opening therethrough for guiding the belt of linked ammunition in sliding relation therethrough, a sprocket rotatably mounted upon said frame to engage said ammunition belt in geared relation, a tensionable coil spring coupled at one end to said sprocket, motor means coupled to the other end of said spring for driving said sprocket through said spring whereby said spring comprises an elastic sprocket-motor coupling device for rotating said sprocket to motivate said ammunition belt in gun feeding direction, ratchet means associated with said sprocket to prevent rotation thereof in ammunition belt gun feeding direction, second ratchet means associated with said motor means to prevent reverse rotation of the latter intermediately of gun feeding ammunition belt driving operations, crank means coupled to said first mentioned ratchet means and having ammunition belt bearing means adapted to engage against the ammunition belt between the positions of said feed device and the associated gun, said crank means being arranged to be actuated upon tensioning of that portion of the ammunition belt bearing against said crank means to release said first mentioned ratchet means, motor control switch means mounted upon said frame and arranged to be actuated by movement of said crank member in ratchet release direction for energizing said motor means, and spring means associated with said crank member for returning the latter

to motor-deenergized and ratchet engaged position upon slackening of the ammunition belt in the region of said crank bearing means.

4. An ammunition feed device comprising, a frame having an opening therethrough for guiding a belt of linked ammunition sliding therethrough, a member movably mounted upon said frame to engage said ammunition belt in geared relation, a tensionable spring coupled at one end to said member, motor means coupled to the other end of said spring whereby said spring comprises an elastic drive coupling device, ratchet means associated with said member to prevent movement thereof in ammunition belt feed direction, ratchet means associated with said motor to prevent reverse operation of the latter intermediate of ammunition belt driving operations, crank means coupled to said first mentioned ratchet means and having ammunition belt bearing means adapted to engage against the ammunition belt as it issues from said feed device, said crank being arranged to be actuated upon tensioning of the issuing portion of the ammunition belt to release said first mentioned ratchet means, motor control means mounted upon said frame and arranged to be actuated by movement of said crank member in ratchet release

direction, and spring means associated with said crank member for returning the latter to motor-inoperative and ratchet engaged position upon slackening of the issuing ammunition belt portion.

5. An accessory device for use in conjunction with a machine gun or the like for motivating a linked ammunition belt into the region of the gun, comprising in combination a base, a belt engaging member carried by said base, motor means, elastic coupling means interconnecting said belt engaging member and said motor means, a stop member carried by said base and movable to stop or release said belt engaging member, movable crank means connected to said stop member to engage the ammunition belt between the positions of the gun and said accessory device for actuating said stop member in response to alternate slackening and tightening of said ammunition belt portion, motor control means connected to said stop member and operable in response to movement thereof to control operation of said motor means, and means associated with said motor means to prevent reverse operation thereof.
